UNITED STATES PATENT OFFICE.

FLAVIUS J. BROWN, OF PLEMONS, TEXAS, ASSIGNOR OF ONE-FOURTH TO A. M. LASATER, OF PLEMONS, TEXAS.

BAG-FASTENER.

943,175.

Specification of Letters Patent. Patented Dec. 14, 1909.

Application filed April 20, 1909. Serial No. 491,017.

To all whom it may concern:

Be it known that I, FLAVIUS J. BROWN, a citizen of the United States, residing at Plemons, in the county of Hutchinson and State of Texas, have invented certain new and useful Improvements in Bag-Fasteners, of which the following is a specification.

The object of this invention is to provide extremely simple but effective locking means for hand bags, satchels, purses, or the like.

The particular aim of the invention is to secure a locking mechanism for articles of this class and which is readily operable by one hand in order to disengage the locking devices from the portions of the frame of the hand-bag engaged thereby, the manner of operating the locking mechanism being extremely simple and convenient so as to make the same especially desirable for use by physicians and persons having only one arm.

For a full understanding of the invention, reference is to be had to the following detail description and to the accompanying drawings, in which—

Figure 1 is a side elevation showing the hand-bag to which the invention is applied; Fig. 2 is a longitudinal sectional view bringing out more clearly the mounting of the locking mechanism on the frame of the hand bag, the parts being shown in dotted line positions as when operated to release the locking mechanism; Fig. 3 is a transverse section taken about on the line 3—3 of Fig. 2; and Fig. 4 is a section taken about on the line 4—4 of Fig. 2.

Throughout the following detail description and on the several figures of the drawings similar parts are referred to by like reference characters.

In carrying out the invention, the same is adapted for application for handbags of various sizes and types, a conventional type being illustrated in the drawings.

Describing specifically the construction of the invention in the drawings 1 denotes the handbag which is provided with a suitable handle 2 connected therewith in any convenient manner. The bag 2 is provided with the usual frame composed of sections 3 and 4 pivotally connected together at their lower portions in a manner not shown, but which is common in articles of this class. The frame section 3 is adapted to fit at its upper portion in the frame section 4 as shown most clearly in Figs. 3 and 4, the end

portions of the section 4 being provided with sockets 5 pressed outwardly or otherwise formed therein.

The section 3 of the frame has openings 6 adapted to register with the sockets 5 and through the openings 6 are adapted to slide the ends of latch bolts 7. The bolts 7 are mounted in bearings or openings in brackets 8 secured to the underside of the top of the section 4 of the frame and said bolts are freely slideable longitudinally in said brackets. Springs 9 connected with the bolts and preferably located between the ends of the brackets 8 are adapted to normally tend to project the bolts 7 outwardly so as to engage in the sockets 5 when the frame sections are brought together in closing the bag.

At the central portion of the frame section 4 and pivotally mounted on a pivot 10 carried by said section are the levers 11 by which the bolts 7 are operated. The pivotal ends of the levers 11 cross one another and each lever has its lower end connected with the sliding bolt 7 more remote from said lever. In other words diagonally opposite levers and bolts are connected together, the levers being adapted to be simultaneously lifted into the dotted line positions shown in Fig. 2, in order to withdraw the bolts 7 from the sockets 5. The adjacent ends of the levers 11 and bolts 7 are pivotally connected and the action of the parts is readily apparent by reference to Fig. 2.

On the outer ends of the levers 11 are finger loops 11^a on the lower sides of which are formed the U-shaped catches 11^b preferably integral therewith. The purpose of the catches 11^b is to embrace the frame sections 3 and 4 on opposite sides so that these sections are firmly held in closed positions by the co-operation of the catches 11^b and the sliding bolts 7.

To open the satchel it is only necessary to raise the levers 11 thus disengaging the catches 11^b from the sections of the frame and simultaneously disengaging the bolts 7 from the sockets 5.

As a convenient means for locking the hand bag closed a lock may be applied at the central portion of the section 3, said section having a keyhole opening 12 for the introduction of a key that is adapted to actuate a lock bolt 13 vertically movable be-

tween the adjacent ends of the bolts 7, as shown in Fig. 3. When the bolt 13 is in the position shown in full lines in Figs. 2 and 3, the bolts 7 are locked from movement and the levers 11 cannot be received. When, however, the bolt 13 is moved downwardly into the position shown in dotted lines in Fig. 3 the satchel may be readily opened.

10 It may be noted that the levers 11 may be made of any suitable size and will of course be smaller in proportion when the locking device comprising the invention is used in connection with bags of a size considerably larger than illustrated in Fig. 1.

15 Various modifications of the details of construction of the invention may be resorted to within the spirit thereof.

Having thus described the invention, what 20 is claimed as new is:

1. In combination, a handbag embodying frame sections adapted to open and close with respect to one another, latch bolts mounted for movement in opposite directions on one of the frame sections and adapted to engage the other section, a pair of levers each lever being connected with one of the bolts, a pivot common to both levers, means normally tending to hold the bolts in engagement with the sections to lock the 25 30

same closed, and catches carried by the levers to engage the frame sections to lock the same closed.

2. A handbag comprising frame sections adapted to open and close with respect to one another, bolts mounted on one section and arranged to engage the other section to lock the two sections closed, levers for operation of said bolts, and catches carried by the levers exterior to the bag to engage and hold the frame sections together when both of said sections are engaged by the bolts.

3. A handbag comprising frame sections, oppositely sliding bolts on one section, the other section having sockets to receive said bolts, levers on the section carrying the bolts, a pivot common to said levers, pivotal connections between the levers and bolts, the levers being exterior to the frame sections and movable toward one another to release the bolts from their sockets, and U-shaped catches carried by the outer ends of the levers to embrace the frame sections and hold the same together.

In testimony whereof I affix my signature 55 in presence of two witnesses.

FLAVIUS J. BROWN.
